CLAIM

A stitching protector for flexible straps, as shown and described.

DESCRIPTION

FIG. 1 is a perspective view of the stitching protector for flexible straps;

FIG. 2 is a front view of the stitching protector for flexible straps of FIG. 1;

FIG. 3 is a back view of the stitching protector for flexible straps of FIG. 1;

FIGS. 4 and 5 are the left and right side views of the stitching protector for flexible straps of FIG. 1; and, FIGS. 6 and 7 are the top and bottom views of the stitching protector for flexible straps of FIG. 1.

The broken line portions of the drawings are for illustrative purposes only and form no part of the claimed design.
